Patented Aug. 20, 1901.

M. A. HAMILTON.
ACETYLENE GAS GENERATOR.

(Application filed Sept. 11, 1899.)

(No Model.)

UNITED STATES PATENT OFFICE.

MILTON A. HAMILTON, OF DETROIT, MICHIGAN.

ACETYLENE-GAS GENERATOR.

SPECIFICATION forming part of Letters Patent No. 680,858, dated August 20, 1901.

Application filed September 11, 1899. Serial No. 730,137. (No model.)

To all whom it may concern:

Be it known that I, MILTON A. HAMILTON, a citizen of the United States, residing at Detroit, in the county of Wayne and State of Michigan, have invented certain new and useful Improvements in Acetylene-Gas Machines, of which the following is a specification, reference being had therein to the accompanying drawings.

10 The invention consists in the construction of an acetylene-gas generator, and particularly in the following particulars: First, in the construction of a generator whereby the gas is dried and purified before passing into the mains; second, in the construction of a generator having a controlling device which maintains a uniform pressure in the mains regardless of the volume of gas which may be used, and, further, in the construction, 15 arrangement, and combination of the various parts, as more fully hereinafter described, and specifically pointed out in the claims.

In the drawings, Figure 1 is a side elevation of my improved generator, showing two tanks 20 or generator-chambers, one in section and one in elevation. Fig. 2 is a sectional elevation of a controlling-valve for the pressure in the mains. Fig. 3 is an elevation of the upper part of one of the generators, showing 25 the cap turned to one side to remove the carbide vessels. Fig. 4 is a side elevation of the generators, illustrating the manner of connecting the water-supply thereto. Fig. 5 is a section through one edge of the cap, 30 illustrating the joint between the cap and the body of the generator.

While I have shown and prefer to use two generating-tanks A and B, connected together, the broader features of my invention will be 35 found to be embodied in a single tank which is provided with the other features of my invention, as hereinafter set forth.

The tanks A and B are provided at the top with caps C, which are supported in a yoke 40 D, one end of the yoke being hinged to an ear E on the top of the tank and the other being provided with suitable connecting means to an ear or lug F upon the opposite side. When the yoke is swung upon its 45 hinge, it carries with it the cap, and it may be turned to the open position shown in Fig. 50 3 or to the closed position shown in Figs. 1

and 4. In the closed position, the yoke being connected to the two ears rigidly, the hand-wheel F' may be employed to screw down the 55 cap tightly against the top of the receptacle to make a tight joint. This joint I preferably make as shown in Fig. 5.

The upper wall or edge of the generator-body I provide with two flanges a and b of 60 different heights, forming a well c between, and the rim of the cap I form with a depending lip d, having an inclined inner surface adapted to bear against the outer wall of the flange b, as shown in the drawings. Between 65 the wall b and the under face of the cap I preferably arrange a packing e, as shown. The flange d dips into the well c, and if this well is filled with water or other fluid I can readily ascertain if the cap leaks by the bubbles passing through the joint thus sealed.

H is the carbide-receptacle, which is in the nature of a perforated vessel suspended or supported centrally near the lower end of the generator A. I have shown and I believe it 75 is the preferable construction to suspend this vessel H by means of a rod I from another vessel J, likewise perforated and suspended in the top of the generator-chamber by any suitable suspending means, such as a cross-bar a² and a suitable hook a³, the two vessels being of such diameter that they can be readily withdrawn from the generator-chamber when the cap is removed.

I provide at the bottom of the generator-chamber, which is shown in the nature of a vertical cylinder, a valved exit K, which may be used to thoroughly wash out and cleanse the interior thereof when the carbide-receptacles are removed. I also provide a gage L on 80 the side to indicate the height of the water, and I may employ a cock M for drawing off the water from the generator whenever desired.

O is the exit-pipe for the gas from the top 85 of the generator. This leads into the main O', which carries the gas to the burners. I have shown both generators connected to the main O' by a similar pipe O and each provided with a valve P between the generator 90 and the main, so that either or both generators may be connected to the main, as desired.

Q is the water-tank, which is arranged at such a height as to give the desired hydro-

static pressure to the water flowing into the tank or generator.

Q' is the water-supply pipe to the tank, and in this case I have shown it extending down 5 to about the middle of the generator and connected through the valved branch pipes R into both generating-tanks A B, each branch pipe being provided with a suitable controlling-valve S. The water-supply pipe has in 10 it a check-valve T, and it is evident that as long as the pressure in the generator is less than the hydrostatic pressure of the water the water will continue to flow into the generator and upon the carbid therein to generate gas; but when the pressure in the generator exceeds the hydrostatic pressure of the water the gas-pressure will then close the check-valve and shut off the water-supply automatically.

20 When I am using the tank A, I first discharge the gas into the tank B by means of a pipe 11 and thence through the conduit or supply-pipe O, and when I use the tank B, I discharge the gas therefrom into the tank 25 A through a corresponding pipe U', these pipes being provided with suitable shut-off valves V.

When using the tank A as the generator and discharging into the tank B, the tank B 30 becomes a part of the conduit and acts as a settling-chamber and a partial condenser for the gas before going out into the rest of the main, and in such use the tank B forms, in effect, a part of the conduit or main from the 35 generator to the burners.

In order to control the pressure of the gas in the main and maintain it at as nearly uniform pressure as possible regardless of the number of lights that may be used, I employ 40 a controlling-valve for the gas-supply for the generator into the main and control that valve by the pressure in the main. This valve is shown in detail in Fig. 2 and is shown in elevation in Fig. 1 within the generator A. 45 The valve proper, i, has a stem k, which passes through a stuffing-box l and into a casing m. In this casing is a diaphragm n, to which the end of the stem k is secured. Between the diaphragm n and the stuffing-box l is an air- 50 chamber o, in which I desire to maintain substantially atmospheric pressure, and this I preferably accomplish by first making the packing-joint l and the diaphragm n airtight, and, second, by a pipe or nipple p, 55 preferably having a cock r leading into the atmosphere, so that if by any chance gas under pressure should get into the chamber o I may reduce it to atmospheric pressure by opening the cock r. The chamber q below 60 the diaphragm I connect by a pipe s with the conduit or, preferably, with the tank B, which, as before described, forms, in effect, a part of the conduit.

Supposing the tank A to be used as the generator and the tank B as a storage-tank or 65 part of the conduit or main, the operation of the parts is as follows: The tank Q being sup-

plied with water and the receptacles H and J being in position, the receptacle H being charged with carbide of calcium and the receptacle J being preferably charged with the same material, the valve S leading into the generator A is opened and a small supply of water will be delivered into operative relation to the carbide in the receptacle H, thereby 70 producing the acetylene gas. This gas will rise into the upper part of the generator A and will pass over and in contact with the carbide in the receptacle J, which, as is well known, has great affinity for water and will 75 extract a large proportion of the moisture from the gas thus generated. The gas thus formed will pass out through the pipe U, the valve V being open, and thence into the tank B. In this tank the gas will be further dried 80 and purified besides being enriched by the moisture in the gas being absorbed by the dry carbide suspended therein. The exit-valve from the top of the tank B being open to the main O', the gas will pass out therefrom. When the pressure in the tank B rises above the normal pressure desired, the valve i will be closed by the pressure of the gas, which will pass through the pipe s and act 85 on the under side of the diaphragm n to 90 operate that valve. The pressure desired to close the valve i is controlled by a weight applied to the valve. This I preferably form by means of a cup t on the valve-stem, containing shot or other similar material, the amount of which may be varied so that any desired weight can be maintained to resist the gas-pressure. The air in this chamber o in the valve-casing assists in this closing. 95 As soon as the pressure in the tank B is reduced to normal the weighted valve will automatically open, and the pressure from the tank A can pass into the tank B and raise it to its normal pressure. This action is so 100 quick that it practically requires no appreciable diminution of pressure in the tank B before the valve opens and again balances the pressure. Below the pipe s is a connecting-pipe s' between the two tanks, with a shut-off and check valve therein oppositely arranged to those in the pipe s. This pipe s' connects into a controlling-valve in the generator-casing B, which controls the pipe U', leading from the tank or generator to the tank or generator B, in the same manner as 105 described for the controlling-valve in the generator A. As before described, it requires this construction to get the benefit of my using two tanks, either one of which may be the main generator, as hereinbefore set forth. 110

By having the controlling-valve inside of the tank Q there is no back pressure to open the valve, and I am enabled to get an adjustment that is not possible with a valve located on the outside thereof. Also, any leakage 115 from the valve-casing is not detrimental, because it would simply leak into the generator itself.

It will be obvious that instead of having a

second tank into which to allow the gas to pass after being generated and there to be enriched and dried by dry carbid I may make the gas-chamber in the first tank sufficiently 5 large and supplied with a sufficient amount of dried carbid to effect the same result. It is desirable that this dry carbid should be in a gas space or chamber entirely free from the generating carbid-receptacle, so that at no 10 time in the operation of the machine would the gas go off without the purifying and drying effect of the dry carbid.

What I claim as my invention is—

1. The combination of a tank or vessel, a 15 carbid-receptacle therein, a water-supply thereto, and a gas-exit therefrom, a second tank to which said exit connects, a connection from said second tank to the main supply, a pressure-controlling valve in the first 20 tank, and a connection from said second tank to said valve.

2. The combination of two tanks each having carbid-receptacles water-supply connections and gas-exits, a pressure-controlling 25 valve in each tank for its exit-pipe, cross con-

nnections from the opposite tank to each pressure-controlling valve and shut-off valves for the various pipes.

3. In an acetylene-gas generator comprising two tanks, carbid-receptacles in both tanks, controlled water-supply to both tanks, gas-exit pipes from both tanks and valve-controlled gas connections whereby either tank may be used as a generator and the other tank as a condensing and enriching receptacle for 35 the gas.

4. In an acetylene-gas generator, the combination of two tanks or vessels, a carbid-receptacle in each, a water-supply thereto, and gas-exits therefrom to a common main, a pressure-controlling valve in each tank having an exit leading to the other tank and a cross 40 connection from each tank to said valve to actuate the pressure-controlling valves.

In testimony whereof I affix my signature 45 in presence of two witnesses.

MILTON A. HAMILTON.
